UNITED STATES PATENT OFFICE.

GEORGE C. WEBSTER, OF LOS ANGELES, CALIFORNIA.

SASH BALANCE.

Application filed October 21, 1922. Serial No. 595,948.

To all whom it may concern:

Be it known that I, GEORGE C. WEBSTER, a citizen of the United States, residing at Los Angeles, in the county of Los Angeles and State of California, have invented new and useful Improvements in Sash Balances, of which the following is a specification.

This invention relates to sash balancing means, and has for its object to improve the 10 type of sash balance that is disclosed in a patent issued November 27, 1917, No. 1,248,221.

More particularly it is an object of the present invention to provide a simplified and 15 easily acting type of sash supporting means, and particularly it is an object to provide a sash balancing means consisting of few and substantial parts including a spring adapted to be wound and unwound by the action of 20 the sash.

Other objects and advantages will be made manifest in the following specification of an embodiment of the invention illustrated in the accompanying drawings, 25 wherein—

Figure 1 is a view showing in elevation and partial section fragments of upper and lower sashes combined with the improved supporting means.

Fig. 2 is a longitudinal section through 30 one of the sash supporting means detached from the window.

Fig. 3 is a plan of the supporting device. The invention is shown as combined with 35 an upper vertically sliding sash 10 and a lower similarly sliding sash 11, each of which has its side stiles 12 longitudinally channeled for a suitable length; the top and bottom ends of the rails 13 closing the ends

40 of the channels in the stiles. The present invention consists broadly of a tube 15 of suitable diameter and length and being provided with a helical groove 16 of a suitable pitch; the groove preferably being of arcuate cross section.

An inexpensive form of the device is shown wherein the tube 15 has the helical groove rolled or inwardly depressed therein. The upper end of the tube, or as it may be called the roller 15, is provided with a cap 17, and the lower end is provided with a similar cap 18 each of cup form; the lower cap being shown as provided with a struck down lug 19 to receive and hold the contiguous end of an appropriately strong spring 20 arranged within the roller 15 and sur-

rounding a spindle 21, the ends of which are turnably mounted in the caps 17 and 18. One end of the spring 20 is shown as attached to the spindle 21 which is shown as 60 having an aperture 22 to receive the contiguous end of the spring.

The organized unit consisting of the roller 15 and its spring and spindle is adapted to be countersunk in the longitudinal channel of a slide stile 12 and attached thereto. 65

The attaching means may consist of an upper bracket 23 having a downwardly extending arm 24 which may be nailed as at 70 25 to the bottom of the channel in the stile 12, and the bracket has an upwardly bent outer end 26 which is secured as by a nail 27 to the end of the top rail 13 of a sash. The bracket 23 is provided with an elongated aperture 28 to receive the noncircular 75 or flat end 21' of the spindle 21 and therefore hold this against rotation.

A somewhat similar lower bracket 30 is secured to the bottom stile of the window sash 11 and has a socket portion 31 to receive the lower end of the spindle 21. These 80 brackets therefore support the spindle 21 in upright position and permit the rotation of the roller or tube 15 about the spindle.

Countersunk in the adjacent vertical element 33 of the window frame is a device 85 consisting of a collar 34 rotatably fitting about the roller 15, the collar having the transversely extending shell 35 which is countersunk in the window frame 33 as clearly shown in Fig. 1. The shell or lateral extension 35 is provided with a ball race 36 and in it is arranged an annular series of balls 37 which support centrally a large roller engaging ball 38, this having a diameter 90 complementary to the arcuate helical groove 16 in the roller 15. It will be seen that by this construction the contact roller 38 will freely roll on its annular series of ball bearings 37 during vertical movement of the 95 roller 15 with the respective window sash.

In action, when the sash is raised or lowered, the nonshifting roller engaging ball 38 is effective to cause the rotation of the roller 15 about its own axis. This rotation 100 of the roller on the downward movement of the sash causes the spring 20 to be wound to increase its tension and therefore form an effective counterbalance and support to hold the window sash in any adjusted position in its guides. 110

From the above it will be seen that the

present improvement enables the easy action of the sash due to the antifriction support of the roller engaging ball 38. It will also be seen that I have provided a window supporting means or counterbalance of extreme simplicity and few and substantial parts.

The brackets are shown as provided with slight projecting beads 30' which are provided for the purpose of having a running contact with the window frames and taking all of the wear, and for providing for operation of the sash with minimum friction.

Further embodiments, modifications and changes may be resorted to within the spirit of the invention as here claimed.

What is claimed is:

1. A yielding sash counterbalance comprising upper and lower brackets, a roller adapted to be countersunk in a stile of a window sash, a spindle extending through the roller and adapted to be mounted and held against rotation in said brackets, a spring surrounding said spindle and secured thereto and inclosed in said roller, and being attached at one end thereto, and a ball and race device attachable to a contiguous member of the window frame for supporting a ball engaging and causing the roller to rotate during movement of the sash and thereby vary the reaction of the spring.

2. A yielding sash counterbalance comprising upper and lower brackets, a roller adapted to be countersunk in a stile of a window sash, a spindle extending through the roller and adapted to be mounted and held against rotation in said brackets, a spring surrounding said spindle and secured thereto and inclosed in said roller, and being attached at one end thereto, and means attachable to a contiguous member of the window frame for engaging and causing the roller to rotate during movement of the sash

and thereby vary the reaction of the spring, said means including a ball bearing adapted to be held in said position by the window frame, and a roller engaging central ball supported on the ball bearing.

3. In a spring controlled, roller sash counterbalancing means, a roller having a peripheral, helical groove, a ball engaging said groove, which is free to turn upon a nest of balls within a ball race.

4. In a spring controlled, roller sash counterbalancing means, a tubular roller having a peripheral, helical groove depressed in its wall, end caps applied to the ends of the roller, a spindle extending axially of the roller and journaled in the caps and extending beyond the same, and a spring surrounding the spindle and attached at one of its ends thereto and attached at its opposite end to one of the caps so that upon relative rotation of the roller and the spindle reaction is produced from the spring.

5. In a spring sash balance, a means for mounting comprising brackets fastened on the inner sides of the top and bottom rails of the window, the rails forming ends for a channel within the window stile in which the sash balance is held, said brackets having recesses receiving ends of the sash balance.

6. In a spring sash balance, a means for mounting comprising brackets fastened on the inner sides of the top and bottom rails of the window, the rails forming ends for a channel within the window stile in which the sash balance is held, said brackets having bead portions in running contact with the window frame.

In testimony whereof I have signed my name to this specification.

GEORGE C. WEBSTER.
